UNITED STATES PATENT OFFICE

GEORGE W. MASON, OF DETROIT, MICHIGAN, ASSIGNOR TO COPELAND PRODUCTS, INC.,
A CORPORATION OF MICHIGAN

REFRIGERATION APPARATUS

Application filed March 26, 1930. Serial No. 439,014.

It is one of the primary objects of my invention to provide a simple and economical construction of expansion chamber or freezer coupled with a refrigerant tank of simple design. More specifically, my invention encompasses the making of an expansion chamber of the sheet metal type with the refrigerant tank formed integrally therewith.

Another object of my invention is to provide a simple and economical assembly of operating parts for the refrigerant tank.

With the above and other objects in view, my invention consists in the arrangement, combination and construction of the various parts of my improved device, as described in the specification, claimed in my claims and shown in the accompanying drawings, in which:

Fig. 1 is a transverse sectional view of an expansion chamber and refrigerant tank embodying my invention.

Fig. 2 is a similar view showing a modification of the device shown in Fig. 1.

Fig. 3 is a sectional view taken on line 3—3 of Fig. 1.

In the construction as illustrated in Figs. 1 and 3, I have shown a conventional sheet metal type expansion chamber which is composed of superposed sheets of metal 5 and 6 the edges of which may be suitably sealed such as at 7, by welding or other suitable means and the intermediate portions of which may be spot-welded together as at 8 to form a devious passage for the refrigerant which is fed thereto from the refrigerant tank 9. The body portion of the tank 9 is formed as an integral extension of the sheet 6, as particularly shown in Fig. 1, and the outer end or edge of the sheet may be welded or otherwise secured and sealed to the sheet 5 as at 10.

A sheet metal end 11 may be secured to the end of the body portion of the tank 9 as at 12, and an end 13 may be secured at the other end of the body portion of the tank by means of studs 14. A suitable washer or gasket 15 may be provided to seal the joint.

Integral with the end element 13 is the inlet conduit or passage 16 which may be connected with a pipe 17 leading to a source of supply. An elevated nipple integral with end 13, is

shown as downwardly apertured to form a seat opening 18, from the conduit 16 to the tank proper, and this opening is adapted to be closed by means such as an upwardly seating needle valve 19 which is shown as provided on the swinging arm 20, intermediate the ends thereof. The arm 20 is pivoted at one end, as at 21, to a substantially central lug 22 on the end 13. The other end of arm 20 is provided with a float 23 which is adapted to rise as the level of the refrigerant in the tank 9 rises until the needle valve 19 is brought to its seat in the aperture 18, thus closing the supply passage until refrigerant has been passed off from the tank 9 into the freezer or expansion chamber 24.

In the modified construction shown in Fig. 2, the freezer or expansion chamber 24 is similarly formed by the use of sheets 5 and 6 and the refrigerant tank is composed of the integral and oppositely concave extensions 26 and 27 from the sheets 6 and 5, respectively. In this construction, a fitting 28 is provided on the sheet 5 and has an aperture which opens, substantially at the level of the lower-most refrigerant passages, into the expansion chamber 24, the edges of the fitting being sealed in any suitable manner with the face of the sheet 5. A lug or ear 29 depends from the fitting 28 and a channeled rod 30 is pivoted thereto as at 31. The rod 30 has a ball 32 on the other end thereof acting as a float and a valve 33 adapted to seat in the fitting 28 as at 34 is provided with a screw threaded stem 35 which engages the nut 36 held in the channel of the rod 30 against rotation. In this construction the float and its valve are assembled as shown in Fig. 2, the position of the float adjusted by turning the valve 33, and then the inlet pipe (not shown) is sealed in the fitting through the screw threads 37.

It will be obvious that in both forms, a simple and economical refrigerant tank and expansion chamber of freezer construction is shown, as well as a simple and economical valve assembly.

It will be obvious that various changes may be made in the arrangement, combination and construction of the various parts of my improved device without departing from the

spirit of my invention, and it is my intention to cover by my claims such changes as may be reasonably included within the scope thereof.

5. What I claim is:

1. In combination, a freezer for refrigeration systems composed of superposed sheets of metal having refrigerant passages between them and a float controlled refrigerant tank integrally connected with the freezer, said tank being positioned substantially on the level of the lowermost of said passages.
2. In combination, a freezer for refrigeration systems, composed of superposed sheets of metal having refrigerant passages between them, a sheet metal refrigerant tank body formed as an integral extension of one of said sheets and connected with the freezer refrigerant passages,—said tank having end elements, and at least one end element of said tank being separately formed and secured in the body of the tank, said end element having both a substantially central pivot lug and an apertured inlet nipple formed therein, and a float arm terminally pivoted to said lug and intermediately provided with a valve cooperating with the apertures in said nipple.
3. In combination, a freezer for refrigeration systems, composed of superposed sheets of metal having refrigerant passages between them, a sheet metal refrigerant tank body formed as an integral extension of one of said sheets and connected with the freezer refrigerant passages,—said tank having end elements, and at least one end element of said tank being separately formed and secured in the body of the tank, said end element having both a substantially central pivot lug and a downwardly apertured nipple formed therein, and a float arm terminally pivoted to said lug and intermediately provided with a valve upwardly cooperating with the aperture in said nipple.
4. In combination, a freezer for refrigeration systems composed of superposed sheets of metal having refrigerant passages between them, and a float-controlled refrigerant tank integrally connected with said freezer, said tank being positioned substantially on the level of the lowermost of said passages and formed by oppositely concave extensions of said sheets.
5. In combination, a freezer for refrigeration systems comprising superposed sheets of metal having refrigerant passages between them, a float controlled refrigerant tank integrally connected with said freezer,—said tank being positioned substantially on the level of the lowermost of said passages and formed by oppositely concave extensions of said sheets, and one of said sheets being apertured substantially at said level and there provided with a valve seat fitting.
6. In combination, a pair of generally spaced sheet metal plates sealed together at

their edges, a tank integrally connected to and in constant communication with, the space between said sheets,—said tank being formed by oppositely concave extensions of said sheet—valve means, at an opening provided with a seat fitting for feeding said refrigerant through one of said sheets into said tank, and a float, pivotally carried by said fitting, for controlling the level of the refrigerant in said tank by manipulation of said valve.

7. An integral freezing and float chamber for refrigerating mechanisms comprising a pair of generally spaced sheet metal plates sealed at their edges to form a continuous passage between them and further formed to provide a bottom chamber for the reception of liquid refrigerant, means for introducing liquid refrigerant into said chamber and means for maintaining said liquid refrigerant at a predetermined level in said chamber.

8. In combination, a pair of generally spaced sheet metal plates sealed together at their edges to form a refrigerant passage between them, an enlargement adjacent the bottom of said sheets and connected with said passage formed by an extension of at least one of said sheets, said enlargement being provided with an open end, a cover for closing said end, means for introducing refrigerant into said enlargement, and a float mechanism carried by said cover for controlling the flow of liquid refrigerant to said enlargement.
